UNITED STATES PATENT OFFICE.

SALAMON LEBENSART, OF VIENNA, AUSTRIA.

EXPLOSIVE PROJECTILE.

Application filed June 11, 1925, Serial No. 36,502, and in Austria July 17, 1924.

This invention relates to explosive projectiles, and more particularly to the type of projectiles generally known as hand-grenades or, simply, as grenades; one of its objects being to provide an improved percussion fuse which will be exploded even on striking soft, swampy, or any other kind of non-coherent ground or whether it be covered by water or snow and so on. The great sensitiveness necessary for such action constitutes, of course, a great danger for the troops also and in order to avoid this danger, I have provided various new and improved safety devices eliminating every undesired explosion in any case which practically may occur. Other and further objects and improvements are comprised in the invention and will be explained in the course of the following detailed description.

20 The accompanying drawings illustrate one embodiment of the invention, and therein:

Fig. 1 represents a longitudinal sectional view of a small hand-grenade, the right half of the figure showing the parts of the fuse 25 in section, and the left part of the figure in elevation;

Fig. 2 shows the fuse in transverse section on the broken line 2—2, Fig. 1;

Figs. 3 and 4 represent details of the construction;

Figs. 5^A—8^B represent longitudinal sectional views of the inner parts of the fuse in their different positions assumed during the working of the hand-grenade, each figure showing only one half of the fuse, the other half being symmetrical to that represented.

Referring more particularly to the drawings, U designates the casing of the grenade, which may vary in form and construction in practice to meet different requirements. The said casing is made of sheet metal and is provided with bosses or ribs U₁ which serve not only to stiffen and strengthen it but also to form a surface of composite or consecutive concave parts U₂ which increase the frictional resistance when the missile strikes the ground, thereby checking its tendency to slide or roll on hard ground or to sink too easily into soft ground.

50 The casing U terminates in a cylindrical portion or rim which fits conformably within and may be threaded or otherwise connected to the correspondingly-shaped rim R₁ provided on the fuse casing R. The explo-

55 charge Y completely fills the space between the casings U and R and may be in powder form, though a compressed block is preferred. The inner portion of the fuse casing terminates in a neck of reduced diameter which serves as a holder for the detonator 60 cap X, Fig. 1.

The detonating charge in cap X is ignited by the explosion of a percussion cap or primer B₁ which is itself detonated by a firing pin A₁ in the manner subsequently explained. 65 The percussion cap B₁ is mounted in a holder which constitutes the lower portion or stem of a funnel-shaped, sheet metal member B₃.

The previously mentioned funnel or cone B₃ is provided with a set of upstanding arms 70 B₂, to the upper ends of which a dished or concave-convex shell B is suitably fastened. Six arms have been illustrated in the present instance, Fig. 2, but such number may, of course, be varied; and these arms, together 75 with the cap B₁ and its holder, the cone or funnel B₃ and the shell B conjointly form a single unit which may be called the primer-carrying unit and which is movable bodily to and fro axially of the casing R wherein 80 it is contained.

As stated above, the percussion cap B₁ is ignited by the firing-pin A₁ which is preferably drawn from a second dished shell A of the opposite convexity from shell B. This 85 shell A is provided with upstanding arms A₂ which carry at their upper ends an inwardly bent locking ring A₃ made integral with the arms A₂ of dish A; these arms, together with shell A and locking ring A₃, 90 conjointly form a single unit which may be called the pin-carrying unit and which is also movable bodily to and fro axially of the casing R wherein it is contained.

The arms A₂ and B₂ extend past each other or overlap, as clearly shown on the right half of Fig. 1, thereby associating the two units above referred to like two links of a chain. Moreover, the said two units are mounted in the fuse casing R in such a way as to enable their relative axial sliding movement only but not their rotation, and to effect this, the fuse casing is formed with inwardly-extending longitudinal projections R₂, and on the parts A and B, as well as on the parts attached to them, grooves (Fig. 2) are provided in which said projections are adapted 105 to slide.

Between the shells A and B there is interposed a weight C which acts, at the moment of impact, to ignite the percussion cap B₁ by means of the firing pin A₁. This weight is here shown as spherical, but it may have any other shape desired.

After the two aforementioned units and all parts associated with them have been inserted into the fuse casing R, I attach to the latter a cover S leaving open the mouth of the fuse casing but otherwise adapted to prevent all parts inserted in the fuse casing from falling out therefrom.

All safety-devices employed are mounted in a space within the aforementioned two units in front of the mouth of the fuse casing R.

I employ, first of all, a so called transportation safety-device which serves to render the hand-grenade safe during transportation and has to be released by hand before hurling the grenade.

The second safety-device I employ is a self-releasing one serving to protect the thrower during the action of hurling, i. e. to prevent the hand grenade from being exploded through the impetus given to it during the throwing action, the said safety-device being released automatically after the forces exerted during the action of throwing have ceased to act.

Besides the said two safety-devices which are adapted to be released either by hand or automatically, my construction contains a series of self-locking safety-devices or, briefly, locks serving to prevent automatically the ignition devices from performing their igniting movement in any case in which undesired explosions could occur which would or might be dangerous for the thrower's own troops, the said locks being provided with means preventing them from being released so that they lock the hand-grenade once forever.

All these safety-devices and locks are placed co-axially outside and inside of each other whereby a simple, space saving construction is attained.

The safety member of the self-releasing safety-device consists of a spiral or coil spring L in the form of a ring having a tendency to contract to a smaller diameter, the spirals or coils of the spring, however, being rigid enough to form a stop for the movement of the device in the direction of the axis of the fuse casing R.

The contraction of the spiral ring L is prevented by members E, M, W of substantially sleeve-like form which are associated in a telescopic way, the said members being provided with tapered guiding surfaces or walls and locking recesses which will be described in a more detailed manner in connection with the operation of the grenade. The said members E, M, W derive their movement

from the pin-unit A, A₂, A₃ and the primer-unit B, B₂, B₃ and they permit a contraction of the spiral ring by steps only and, in special cases, they cause a permanent fixing or locking of same.

The safety-device provided for the purpose of securing the parts during transportation comprises a locking member F and an associated spring G; said member taking the form of a sleeve and being provided with a central depending collar F₄, the lower end of which terminates adjacent the shell B. The spring G is encircled by the said member F and bears at one end against member F and at the other end, through members M, W, E, against shell B, so that the percussion cap B₁, which is carried by said shell, is prevented from being ignited by the firing-pin A₁ even though the self-releasing safety device is omitted. Hence, the two safety devices constitute separate means for protecting the firing-pin and percussion cap directly and independently of each other.

The locking ring A₃ and safety member F may be connected together in any desired manner, but preferably by means of interlocks or joints which are analogous to bayonet joints and each of which, as shown in Fig. 3, may comprise an inwardly-projecting lug A₅ formed upon the inner face of the wall of the ring A₃, and a likewise inwardly projecting recess F₂ formed on the safety member F and engageable with the edge of said lug A₅, the recess having a curved surface which normally receives lug A₅ in its central parts and, hence, serves to position the locking member F. The spring G is designed to exert an upward pressure against locking member F and thus maintains the parts F₂ and A₅ in engagement, so that if the locking member F is displaced slightly by some accidental force from its normal position, it will be restored to that position by said spring as soon as such force ceases to act. The lock thus formed may be released by turning the locking member F in either direction, in the manner subsequently explained, so that the release is consequently simplified.

As will be understood from Fig. 1, the collar F₄ of the safety member F does not extend so far inward of the fuse casing as to completely lock the weight C against movement but, on the contrary, a small space or gap is left between the collar end and the shell B, so that weight C, the firing-pin A₁ and the cap B₁ are thus permitted to have a slight play which, of course, is sufficiently less than the distance between the firing-pin A₁ and cap B₁ to prevent ignition of the latter by the former. Furthermore, it will likewise be apparent that the various parts within the fuse, even with the safety devices applied, are resiliently supported or cushioned, so that the shocks and vibrations which are inevitable during transportation will be

transmitted to and taken up by the spring G, whereby the dangers heretofore present from such source are avoided.

In order to unlock the transportation safety device, a releasing means is provided which comprises a set of parts assembled in such a way as to form a water-tight cover for the grenade; the main element thereof being a closure member H and a thin, flexible sheet metal diaphragm J associated with the said closure member and holding it resiliently in place. This member H fits over the top of the fuse casing R and is provided with a curved edge adapted to engage the inclined or tapered outer flange portion of said casing R, adjacent which edge it is formed with a series of projecting lugs H₂ constituting handles for effecting its rotation. At its center, the closure member H is provided with an opening through which passes the locking member F which terminates in a flange F₂ serving to hold the inner edge of the metal diaphragm J, the outer edge of which bears against the closure member H. Between the said closure member H and the cover S, I have inserted a packing ring K which is, accordingly, owing to the action of spring J, under sufficient pressure to form a water-tight joint.

The locking member F is preferably formed with a plurality of depressions or pockets F₁ to receive studs or projections H₁ on the closure member H, so that the two parts F and H will thus rotate in unison when the latter is turned by means of its handles H₂, the rotation of the part F disengaging its recesses F₁ from the lugs A₅ on the locking ring A₃, and thus releasing the transportation safety device.

The diaphragm member J as well as spring G is protected by means of an outer cover Z which may be attached thereto by providing the two parts with interengaging threaded rims, though any other desired connection may be substituted if preferred. The member H may finally be equipped with a device for preventing its accidental rotation; such device consisting of a lead seal, one wire V of which is engaged with the handles H₂, the other wire V₁ with the rim R, of said member H and on the fuse casing R.

It will be apparent from the foregoing and particularly from an inspection of Fig. 1 that the fuse may be entirely assembled and fitted with all safety devices and even with the lead seal before arming it—that is to say, without inserting the percussion and detonating caps B₁ and X. These two caps may be inserted after all other parts of the fuse have been assembled, so that there is no danger whatever in handling the fuse during manufacture. Moreover, the grenade and fuse may be stored in entirely unarmed condition—i. e., without the caps B₁ and X and the bursting charge Y, but otherwise com-

pletely assembled and even equipped with the lead seal.

The grenades are distributed in quantity for use, preferably without the lead seals which may previously be detached. Before throwing, the outer safety device (which is the one used in transportation) is removed by rotating the closure member H in either direction to an extent of about 60-90° by means of its handles H₂, thus unlocking the joints A₅, F₂ between the locking member F and ring A₃, due to the engagement of the projections H₁ and pockets F₁. The safety and cushioning spring G will now act as an expelling spring and will eject the members F and H, together with spring diaphragm J and the outer cover Z, and will itself be removed from the fuse casing, and the spring ring L will thereupon contract and, in so doing jump from the locking member F against which it rests during transportation, into contact with the outer wall M₃ of sleeve M belonging to the self-releasing safety device, Fig. 5^A.

The grenade, then being ready for use, is grasped and hurled in any desired manner, during which operation the weight or ball C will move out of its normal central position owing to its own inertia and to the impetus given to the grenade itself. This movement of the weight has the effect of increasing the distance between the two shells A and B and, consequently, of shortening that between shell B and locking ring A₃, as represented in Fig. 5^B, the shortening of the latter distance, however, being limited by the contact of the spiral spring ring L of the self-releasing safety device with the bosses E₄ of sleeve E. When this contact occurs, the movement of the weight, due to its inertia, ceases but, in the meantime, the spiral spring ring L has left the outer wall M₃ of sleeve M due to the axial shortening of the axial distance between B and A₃, and has snapped beneath the edge M₁ of said wall, thereby coming into contact with the tapered wall E₁ of the sleeve member E, Fig. 5^B. During the throwing operation, however, the spiral spring ring L is pressed outward by the action of the weight C, which action is transmitted to the ring L by means of the shell A, its arms A₂, and its locking ring A₃, and, accordingly, during the operation of throwing the shells A and B are kept locked by the momentum of weight C and abutments E₄, Fig. 5^B, in a position in which the firing pin A₁ has not yet reached the cap B₁; but as soon as the actual throwing operation is completed, and the forces created by the momentum of weight C cease to act, the spiral spring ring L will move upward and inward along the tapered wall E₁ of member E, Fig. 6^A, together with the part M which is pushed forward by spring L, whereupon weight C resumes its normal central position and the

spiral spring L contracts in diameter to an extent sufficient to enable it to pass the edge A₄ of the locking ring A₃, Fig. 6^A. As soon as the spiral spring ring L passes edge A₄, 5 the sleeve member E is left free to be moved away from shell B by a spring D interposed between member E and shell B and, at the same time, sleeve member M is also moved outward by a spring O until it abuts against 10 projections A₆ provided on the locking ring A₃, Fig. 7^A. Spring O is supported by sleeve member E and acts upon the previously mentioned member W which has the form of a sleeve telescoping within the said 15 sleeve member E and transmitting the pressure of spring O to sleeve member M. Sleeve member W is thereby brought to approximately the same level as edge E₃ of sleeve member E so that when the spiral spring ring 20 L contracts and snaps behind the said edge E₃ it comes into engagement with the tapered outer wall of sleeve member W as clearly shown in Fig. 7^A. The self-releasing safety device thus becomes released entirely and 25 the grenade assumes its state ready for ignition in case of striking the ground or target. In order to prevent the said self-releasing safety device from being released too soon or while the grenade is too near to the thrower, 30 I provide means for retarding the release of the safety device. In the embodiment shown, the said means comprise a corrugated undulated slit sleeve Q, Fig. 6^A, which engages the inner slit part E₅ of sleeve member 35 E and is pushed forward by the spiral spring ring L and spring O through sleeve members W and M. By the use of said retarding means, the hand-grenade will be caused to assume its state ready for ignition, Fig. 40 7^A, for instance, after a flight of about six paces only.

Now it may happen that the grenade with the safety device for transportation released, i. e. ready to throw, Fig. 5^A, receives an accidental shock exceeding the momentum of the regular forces created by ordinary throwing; the same may also occur during the action of hurling, Fig. 6^A, but before the state of readiness for ignition, Fig. 7^A, is assumed. In all 45 the said cases coil spring ring L does not move towards the position shown in Fig. 7^A but is forced to engage groove E₂ of sleeve member E, Fig. 6^B, thereby locking once forever the ignition members A₁, B₁ in the 50 position shown in Fig. 7^A in which the firing pin A₁ has not yet reached primer B₁. In order to enable the spiral spring ring L to pass the outer edge of the tapered wall E₁ and the bosses or abutments E₄, Fig. 5^B, when and if such accidental shocks occur, 55 wall E₁, or the wall carrying the abutments E₄, or both, may be slit or otherwise rendered resilient.

If the said undesirable shock does not occur 60 shortly after the throw, then the locking

spring ring L does not pass from its position shown in Fig. 5^B into its locking position, Fig. 6^B, but it will overcome the time retardation effected by slit sleeves Q and E₅ and will get into the position shown in Fig. 7^A 70 which is the position of release. It will be understood that the lock just described is a special safeguard against undesirable shocks at short distances and that the said lock is brought into a condition of readiness 75 or into a sort of cocked position, Fig. 5^B or Fig. 6^A, by the impetus itself given to the grenade through the action of throwing, and it will be also apparent that if the undesirable shock at too near a distance does not occur, 80 the possibility that the said lock may be actuated later is eliminated automatically by the elasticity of spring member L itself which automatically moves into the position 85 shown in Fig. 7^A from which it cannot reach the locking groove E₂ even on impact with the ground. The said lock, of course, must not enter into action in normal cases—i. e. at the regular hurling and regular flight; and in order to prevent the spring member L from 90 engaging the locking groove E₂ in such normal cases, the resistance exerted by the resilient slit member E₁ against the ring L to prevent its passing the abutments E₄ and 95 getting into the locking groove E₂ is rendered so great that it can be overcome neither by the momentum exerted through hurling the grenade nor by the forces of momentum acting upon the grenade during 100 flight but only by shocks. It will be also apparent that the elimination of the lock actuated by shocks at short distances is effected by the locking spiral ring L itself whose elasticity has been freed by the throwing 105 action; the freeing of the said spring ring L, as well as the displacement of same into the positions according to Figs. 5^B and 6^B, being accomplished by one and the same weight or 110 inertia element C.

Now, it may happen that, for some reason, 110 the grenade does not explode on impact with the ground or target. Such blind shells constitute a considerable danger because they may be exploded later through some accidental subsequent shock, for instance when 115 the thrower or his fellows advance, so that it may easily hurt the thrower's own troops. To avoid the said danger, I provide a blind shell lock actuated by the impact of the grenade with the ground or target and comprising means preventing ignition once forever. In the embodiment of my invention shown by way of example in the accompanying drawings, the said blind shell lock comprises the same spiral spring ring L and 120 sleeve members M and W which form part also of the self-releasing safety device and the automatic lock actuated by too short throws already described. For the said purpose, 125 sleeve member M is provided with an in- 130

wardly tapered wall M_2 , Fig. 7^B, the direction of taper of which is opposite to that of wall E_1 of sleeve member E . Now, it may be seen from a comparison of Figs. 7^A and 7^B, that on impact with the ground, ball C , by reason of its inertia, moves shell A toward percussion cap B_1 , thereby igniting said cap through pin A_1 , and at the same time moves the locking ring A_3 and its abutments A_6 , Fig. 7^A, 5 toward shell B , thereby compressing springs D and O to such an extent that if pin A_1 has penetrated into the percussion cap B_1 as shown in Fig. 7^B the combination of the telescoping sleeve members E , W and M assumes 10 its minimum axial dimension. The spiral spring ring L is then forced to snap from the tapered wall of sleeve member W into its cocked position in engagement with the tapered wall M_2 of sleeve member M shown 15 in Fig. 7^B. Now, the spiral spring ring L tends to diminish its diameter and, by exerting a resilient pressure upon groove W_1 of sleeve member W , Fig. 7^B, tends to displace axially the said sleeve members W and M 20 into the position shown in Fig. 8^A. The said tendencies of the spiral spring ring L , however, are checked by the impetus given to the ball C by the impact of the grenade with the ground or target which holds pin A_1 and cap 25 B_1 as well as all parts attached to them in their ignition position, Fig. 7^B, in which pin A_1 has penetrated into cap B_1 , thereby preventing the locking member L from passing 30 into its locking position, Fig. 8^A. Accordingly, as long as the influence of the said 35 impetus will act the spiral spring ring will be held thereby in its cocked position shown in Fig. 7^B but it will pass therefrom into its locking position shown in Fig. 8^A as soon as 40 the impetus of the ball C ceases to act, thereby pulling pin A_1 out of cap B_1 and preventing it once forever from piercing into the cap B_1 again. Of course, the said locking will take 45 place only when and if the grenade gets blind and the fuse is not destroyed by the explosion of the grenade. In order to avoid premature locking suitable means may be provided to retard the movement of sleeve M into its locking position, Fig. 8^A; for instance, the 50 said retarding means for the blind shell lock may be also in the form of corrugated slit sleeves similar to sleeves E_5 , Q shown for the short throw actuated lock, Fig. 6^A. It is an 55 important feature of my blind shell lock that the locking member L is brought into its starting position, Fig. 7^A, only by the actual hurling and flight, whereby premature locking is effectively prevented.

I wish to be understood that the various 60 details of construction may be modified in various respects without in any way departing from the spirit of the invention because my drawings as well as the description are given merely by way of example and in an

explanatory and not in a limitative manner. 65

It is one of the features of my invention that the locking member of the self-releasing safety-device, of the short shock actuated self-locking safety-device and of the blind shell lock is one and the same piece L which 70 I prefer to make in the form of a coil spring ring although each of the said devices or groups of them may be provided with a separate locking member having any suitable form desired. 75

Another feature of my invention is the fact that the helical spring ring L , when moving axially or, rather, perpendicularly to its own plane, performs a peculiar rolling movement which is of high practical value 80 because it reduces to a minimum the resistance or losses owing to friction, thereby diminishing the throwing force absolutely necessary to cause the safety device to be released, and at the same time increasing 85 the sensitiveness of the ignition devices which will ignite even on impact occurring at low velocity on soft ground. This is very important in connection with hand grenades which are thrown with very slight force and 90 low velocity as compared with projectiles fired from a gun.

In the embodiment of my invention shown, the source of power to produce the movement of the ignition devices, of the self-releasing 95 safety-device, of the short shock actuated safety-lock and of the blind shell lock is one and the same weight C which I prefer to make in the form of a ball although each of the said devices or groups of them may 100 be operatively related to a separate weight having any suitable form desired. It will be also seen that I prefer to combine the safety-devices and locks in such a way that the starting position of the blind shell lock 105 is that shown in Fig. 7^A and that the said starting position is identical with the position of release of the self-releasing safety device and of the short shock actuated safety device although such combination need not be used 110 necessarily.

In the embodiment described by way of example, I have shown the primer-carrying-unit and the pin-carrying-unit to be movable only axially of the fuse-casing R . Accordingly, when the grenade strikes the ground in the direction of its axis the weight of either the primer-carrying-unit or of the pin-carrying-unit will assist the ball to produce their firing movement, but when the grenade strikes the ground perpendicularly to the axis of the fuse it is the ball C alone which constitutes the source of power producing the firing movement of the said two units. Now, it is but obvious that I may make the 125 fuse-casing R with a considerable larger diameter than the two said units so that the two units may move within the fuse-cas-

ing R radially too; in that case, I provide the said two units with guiding surfaces in the form of a cone or shell (similar to shell B_3) adapted to slide along similar guiding surfaces provided on casing R, so that the weight of the said units assists the ball C in producing the firing movement of the two units even when the grenade strikes the ground perpendicularly to the axis of the fuse-casing R. Furthermore, it is obvious that in the case just described the ball C may be dispensed with wholly if the two units are made sufficiently heavy to produce the firing movement even without the ball C.

15 In the embodiment described I have shown the weight C to have a pathway or path of travel of abnormal length having an extent equal to at least one-fourth the diameter of the weight and in any case exceeding 3 mm. 20 as I have set out in a more detailed manner in my co-pending application Ser. No. 671,726. Now, the said paths of travel ma , ma_1 , ma_2 , mb etc. Fig. 4, which are necessary to bring the point of the pin A_1 into contact with the surface of the cap B_1 , Fig. 8^B, need not, in connection with my present invention, necessarily be of "abnormal" length but may have an extent as used hitherto.

Further, I have described my invention, 30 by way of example, in connection with a percussion fuse but my invention, however, may be used as well in connection with time-fuses in which the weight C is operatively related to a time ignition device and/or to one or 35 more safety devices of the type described.

I claim as my invention:

1. A projectile, comprising ignition devices; operating means therefor; a safety device operable automatically to lock said operating means against actuation; and means for rendering the safety device inactive; said safety device being brought, by the act of discharging the projectile into an unbalanced position from which it may pass either to its active or its inactive position.

2. A hand-grenade, comprising a firing pin; a universally-movable inertia body to operate the same; a safety device associated with said inertia body to lock it against actuation on impact under predetermined irregular conditions after the grenade has been thrown regularly; and a member for offering resistance to said safety device to prevent its operation by the impetus created 55 during the act of throwing the grenade.

3. A projectile, comprising ignition devices; operating means therefor; a safety device associated with said operating means to lock the same against actuation under predetermined conditions, the safety device including an expandible and contractible helical spring ring which is movable bodily in a direction perpendicular to its own plane for controlling the action of said device;

and means independent of said spring for 65 positively retarding the action of the safety device.

4. A hand-grenade, comprising ignition devices; operating means therefor; a safety device associated with said operating means 70 to lock the same against actuation under predetermined conditions, said safety device including an expandible and contractible coil spring for controlling its action; and a member independent of said spring for offering 75 resistance to the safety device to prevent its operation by the impetus created during the act of throwing the grenade.

5. A hand-grenade, comprising ignition devices; operating means therefor; a self-releasing safety device preventing ignition 80 during the act of throwing, but thereafter permitting ignition; a self-locking safety device automatically locking the ignition devices on impact under predetermined conditions; and means preventing the safety lock from being released automatically.

6. A hand-grenade, comprising ignition devices; a self-releasing safety device preventing ignition during the act of throwing, 90 but thereafter permitting ignition; a self-locking safety device automatically locking the ignition devices on impact under predetermined conditions; and a universally-movable weight for successively operating the two 95 safety devices.

7. A hand-grenade, comprising ignition devices; a self-releasing safety device preventing ignition during the act of throwing, 100 but thereafter permitting ignition; a self-locking safety device automatically locking the ignition devices on impact under predetermined conditions; and a safety member common to the two safety devices for locking them in succession.

8. A hand-grenade, comprising ignition devices; a self-releasing safety device preventing ignition during the act of throwing, 110 but thereafter permitting ignition; a self-locking safety device automatically locking the ignition devices on impact under predetermined conditions; and an expandible and contractible safety ring common to the two safety devices for locking them in succession.

9. A projectile, comprising ignition devices including a firing pin and a primer; a safety device for automatically locking the firing pin against subsequent movement, toward the primer after it has completed an ineffective movement toward the same on 115 impact of the projectile; and a common universally-movable weight operatively related to at least one of said ignition devices and said safety device.

10. A projectile, comprising ignition devices; a safety device for automatically locking said ignition devices against subsequent movement, on ineffective impact, after they 125

- have performed their ignition movement; an expandible and contractible safety ring for controlling the action of the safety device; and operating means for said ignition devices and safety device. 5
11. In a projectile, the combination, with ignition devices, of a self-releasing safety device to prevent actuation of the ignition devices during discharge; a safety device to lock said ignition devices against actuation before they have effected their ignition movement, on impact at too short a distance; and operating means for said ignition and safety devices. 10
12. In a projectile, the combination, with ignition devices, of a self-releasing safety device to prevent actuation of the ignition devices during discharge; a safety device to lock said ignition devices against subsequent movement, on ineffective impact, after they have performed their ignition movement; and operating means for said ignition and safety devices. 15
13. In a projectile, the combination, with ignition devices, of a self-releasing safety device to prevent actuation of the ignition devices during discharge; a safety device to lock said ignition devices against actuation before they have effected their ignition movement; on impact at too short a distance; a safety device to lock said ignition devices against subsequent movement, on ineffective impact, after they have performed their ignition movement; and operating means for said ignition and safety devices. 20
14. A projectile, according to claim 13, in which the operating means for the several safety devices is common to at least two of them. 25
15. A projectile, according to claim 13, in which the operating means for the several safety devices comprises a single universally-movable weight for operating at least two of said devices. 30
16. In a projectile, the combination, with ignition devices, of a self-releasing safety device to prevent actuation of the ignition devices during discharge; a safety device to lock said ignition devices against actuation before they have effected their ignition movement, on impact at too short a distance; a safety device to lock said ignition devices against subsequent movement, on ineffective impact, after they have performed their ignition movement; and operating means for said ignition and safety devices comprising a single member for operating all three safety-devices. 35
17. In a projectile, the combination, with ignition devices, of a self-releasing safety device to prevent actuation of the ignition devices during discharge; a safety device to lock said ignition devices against actuation before they have effected their ignition movement, on impact at too short a distance; a safety device to lock said ignition devices against subsequent movement, on ineffective impact, after they have performed their ignition movement; and a single universally-movable weight to which the ignition devices and all three safety devices are operatively related. 40
18. In a projectile, the combination, with ignition devices, of a self-releasing safety device to prevent actuation of the ignition devices during discharge; a safety device to lock said ignition devices against actuation before they have performed their ignition movement, on impact at too short a distance, at least one safety device including an expandible and contractible annular locking member; and operating means for said safety and ignition devices. 45
19. In a projectile, the combination, with ignition devices, of a self-releasing safety device to prevent actuation of the ignition devices during discharge; a safety device to lock said ignition devices against subsequent movement, on ineffective impact, after they have performed their ignition movement, at least one safety device including an expandible and contractible annular locking member; and operating means for said safety and ignition devices. 50
20. In a projectile, the combination, with ignition devices, of a self-releasing safety device to prevent actuation of the ignition devices during discharge; a safety device to lock said ignition devices against actuation before they have performed their ignition movement on impact at too short a distance; a safety device to lock said ignition devices against subsequent movement, on ineffective impact, after they have performed their ignition movement, at least one safety device including an expandible and contractible annular locking member; and operating means for said safety and ignition devices. 55
21. A projectile, according to claim 19, in which the operating means for the ignition and safety devices in common to at least two of said devices. 60
22. In a projectile, the combination, with ignition devices, of a self-releasing safety device to prevent actuation of the ignition devices during discharge; a safety device to lock said ignition devices against actuation before they have performed their ignition movement, on impact at too short a distance; a safety device to lock said ignition devices against subsequent movement, on ineffective impact, after they have performed their ignition movement, at least one safety device including an expandible and contractible annular locking member, and a single universally-movable weight to which the ignition devices and all three safety devices are operatively related. 65
23. In a projectile, the combination, with ignition devices, of a self-releasing safety de- 70

- vise to prevent actuation of the ignition devices during discharge; a safety device to lock said ignition devices against actuation before they have performed their ignition movement, 5 on impact at too short a distance; a safety device to lock ignition devices against subsequent movement, on ineffective impact, after they have performed their ignition movement; an expansible and contractible annular locking member common to all three safety devices; and operating means for said ignition and safety devices.
24. In a projectile, the combination, with ignition devices, of a self-releasing safety device to prevent actuation of the ignition devices during discharge; a safety device to lock said ignition devices against actuation before they have performed their ignition movement, on impact at too short a distance, 15 a safety device to lock said ignition devices against subsequent movement, on ineffective impact, after they have performed their ignition movement; an expansible and contractible annular locking member common to all three safety devices; and a single operating means common to the ignition devices and all three safety devices.
25. In a projectile, the combination, with ignition devices, of a self-releasing safety device to prevent actuation of the ignition devices during discharge; a safety device to lock said ignition devices against actuation before they have performed their ignition movement, on impact at too short a distance; a safety device to lock said ignition devices against subsequent movement, on ineffective impact, after they have performed their ignition movement; an expansible and contractible annular locking member common to all three safety devices; and a single universally-movable weight to which the ignition devices and all three safety devices are operatively related.
26. In a projectile, the combination, with ignition devices, of a self-releasing safety device to prevent actuation of the ignition devices during discharge; a safety device to lock said ignition devices against actuation before they have performed their ignition movement, on impact at too short a distance; a safety device to lock said ignition devices against subsequent movement, on ineffective impact, after they have performed their ignition movement; a single expansible and contractible coil spring locking ring associated with all three safety devices but operable upon them individually and independently; and operating means for said ignition and safety devices.
27. In a projectile, the combination, with ignition devices, of a self-releasing safety device to prevent actuation of the ignition devices during discharge; a safety device to lock said ignition devices against actuation before they have performed their ignition movement, on impact at too short a distance; a safety device to lock said ignition devices against subsequent movement, on ineffective impact, after they have performed their ignition movement; a single expansible and contractible coil spring locking ring associated with all three safety devices but operable upon them individually and independently; and a single operating means common to the ignition devices and all three safety devices.
28. In a projectile, the combination of ignition devices; a self-releasing safety device to prevent actuation of the ignition devices during discharge; operating means for the safety device; an annular coil spring associated with said safety device to lock the same; and a weight associated with said spring to successively lock and release it.
29. In a projectile, the combination of ignition devices; a safety device to prevent actuation thereof; a coil spring safety ring associated with the safety device; a plurality of inclined guide members to control expansion and contraction of said ring; and operating means for said guide members.
30. In a projectile, the combination of ignition devices; a safety device to prevent actuation thereof; a coil spring safety ring associated with the safety device; a plurality of telescopically-movable guide sleeves having tapered walls for controlling expansion and contraction of said ring; and operating means for said sleeves.
31. In a projectile, the combination of ignition devices; a safety device to prevent actuation thereof; a coil spring safety ring associated with the safety device; a plurality of telescopically-movable guide sleeves having tapered walls for controlling expansion and contraction of said ring, one of the sleeves having a circular recess wherein to catch the ring and thus lock the safety device against movement; and operating means for said sleeves.
32. In a projectile, the combination of ignition devices; a safety device to prevent actuation thereof; a coil spring safety ring associated with the safety device; a plurality of telescopically-movable guide sleeves having tapered walls for controlling expansion and contraction of said ring, one of the sleeves being slit to provide spring tongues which offer radial resistance to said ring; and operating means for said sleeves.
33. In a grenade, the combination of ignition devices; operating means therefor; an expansible and contractible spring ring associated with said operating means; and a member cooperative with said ring to lock the operating means against actuation during the act of throwing the grenade, the ring being movable automatically at the conclusion of the actual throwing operation to unlock said means.
34. In a projectile, the combination of a

pair of oppositely-dished shells, one provided with a firing pin; a weight interposed therebetween; an expansible and contractible spring ring; and a member cooperative with said ring to lock said shells against relative movement under the action of the weight during the actual operation of discharging the projectile, the ring being movable automatically at the conclusion of said discharging operation to unlock said shells.

35. In a projectile, the combination of ignition devices; operating means therefor; an expansible and contractible spring ring associated with said operating means; a member cooperative with said ring to lock the operating means against actuation during the actual operation of discharging the projectile, the ring being movable automatically at the conclusion of said discharging operation to unlock said means; and means for positively retarding such automatic movement so as to delay unlocking.

36. In a projectile, the combination of ignition devices; operating means therefor; an expansible and contractible spring ring associated with said operating means; a member cooperative with said ring to lock the operating means against actuation during the actual operation of discharging the projectile, the ring being movable automatically at the conclusion of said discharging operation to unlock said means; and coacting split rings for positively retarding such automatic movement so as to delay unlocking.

37. In a projectile, the combination of a pair of oppositely-dished shells, one provided with a firing pin; a weight interposed therebetween; an expansible and contractible spring ring; a member cooperative with said ring to lock said shells against relative movement under the action of the weight during the actual operation of discharging the projectile, the ring being movable automatically at the conclusion of said discharging operation to unlock said shells; and means for positively retarding such automatic movement so as to delay unlocking.

38. In a grenade, the combination of ignition devices; operating means therefor; an expansible and contractible spring ring associated with said operating means; a member cooperative with said ring to lock the operating means against actuation during the act of throwing the grenade, the ring being movable automatically at the conclusion of the actual throwing operation to unlock said means; and coacting split rings for positively retarding such automatic movement so as to delay unlocking.

39. In a projectile, the combination, with ignition devices and operating means therefor, of a plurality of independent safety devices operable at different times for controlling ignition; and a single expansible and contractible spring ring common to all the

safety devices for controlling their activity.

40. In a projectile, the combination, with ignition devices and operating means therefor, of a plurality of independent safety devices operable at different times for controlling ignition; and a single expansible and contractible spring ring common to all the safety devices for controlling their activity, said ring having a stepwise or stage contraction incidental to its coaction with the successive safety devices.

41. In a projectile, the combination, with ignition devices and operating means therefor, of a plurality of independent safety devices for controlling ignition embodying telescoping sleeve members of progressively decreasing diameters; and a single expansible and contractible spring ring common to all the safety devices adapted to snap into successive engagement with the different sleeves.

42. In a projectile, the combination of a firing pin; a primer to be ignited; operating means for causing said pin to penetrate the primer on impact of the projectile; and means for withdrawing the pin from the primer after impact unattended by ignition and for locking the pin against subsequent movement toward the primer.

43. In a projectile, the combination of a firing pin; a primer to be ignited thereby; operating means for causing said pin to penetrate the primer on impact of the projectile; an expansible and contractible spring ring; and means operatively associated with said ring to cause the withdrawal of the pin from the primer by said ring after impact unattended by ignition and for locking the pin against subsequent movement toward the primer.

44. In a projectile, the combination of a firing pin; a primer to be ignited thereby; operating means for causing said pin to penetrate the primer on impact of the projectile; means for withdrawing the pin from the primer after impact unattended by ignition and for locking the pin against subsequent movement toward the primer; and means for retarding the locking action of the last-named means.

45. A projectile, comprising ignition devices including a firing pin and a primer; operating means therefor; and a safety device including an expansible and contractible spring ring and sleeve means cooperative therewith for locking said firing pin against subsequent movement toward the primer after it has completed an ineffective movement toward the same on impact of the projectile.

46. A projectile, comprising ignition devices including a firing pin and a primer; operating means therefor; a safety device including an expansible and contractible spring ring for locking said firing pin against subsequent movement toward the primer after

it has completed an ineffective movement toward the same on impact of the projectile; and a single universally movable weight operatively related to said firing pin and said safety device.

47. In a projectile, the combination, with ignition devices, of a self-releasing safety device to prevent actuation of the ignition devices during discharge; a safety device to 10 lock said ignition devices against subsequent actuation, on ineffective impact, after an ignition movement unaccompanied by explosion; both safety devices including in common a continuous, flexible ring for controlling their 15 action, said ring exerting a pressure that is proportionately distributed along its entire circumference; and operating means for said ignition and safety devices.

48. A projectile, comprising ignition devices; a universally-movable inertia body for operating the same; a safety device to control the operation of the ignition devices by said body, the safety device including an expandable and contractible spring ring which is movable bodily in a direction perpendicular to its own plane for controlling the action of said device; and means coacting with the inertia body for transmitting the forces set up by the inertia body always in said direction regardless of the original direction of such forces.

49. A projectile, comprising ignition devices; a universally-movable weight for operating the same by its inertia; a safety device to control the operation of the ignition devices by said weight, the safety device including an expandable and contractible helical spring ring having a rolling motion in a direction perpendicular to its own plane for controlling the action of said device; and

means for transmitting the inertia forces set 40 up by the weight always in said direction regardless of the original direction of such forces.

50. A projectile, comprising ignition devices including a firing pin and a primer; an 45 expandable and contractible spring ring for locking the firing pin against movement toward the primer after it has completed an ineffective movement toward the same on impact of the projectile, said spring ring being 50 movable bodily in a direction perpendicular to its own plane; and a universally-movable weight operatively related to at least one of said ignition devices and said ring.

51. In a projectile, the combination, with 55 ignition devices and operating means therefor, of a plurality of independent safety devices operable at different times for controlling ignition; and a single expandable and contractible spring ring common to all the 60 safety devices for controlling their activity, said ring being movable bodily in a direction perpendicular to its own plane incidental to its coaction with the safety devices.

52. In a projectile, the combination, with 65 ignition devices and operating means therefor, of a plurality of independent safety devices operable at different times for controlling ignition; and a single expandable and 70 contractible spring ring common to all the safety devices for controlling their activity, said ring being movable bodily in a direction perpendicular to its own plane incidental to its coaction with the safety devices and having a stepwise or stage contraction during the 75 course of such movement.

In testimony whereof I affix my signature.
SALAMON LEBENSART.
